Baedwin & Wright

UNITED STATES PATENT OFFICE.

PAUL J. PFEIFER, OF CLEVELAND, OHIO, ASSIGNOR TO THE VIRDEN COMPANY, OF CLEVELAND, OHIO.

ELECTRIC-LIGHT FIXTURE.

1,416,124.

Specification of Letters Patent. Patented May 16, 1922.

Application filed July 11, 1921. Serial No. 483,952.

To all whom it may concern:

Be it known that I, PAUL J. PFEIFER, a citizen of the United States, residing at Cleveland, in the county of Cuyahoga and State of Ohio, have invented certain new and useful Improvements in Electric-Light Fixtures, of which the following is a specification.

This invention relates to brackets for side lights and the object of the invention is to construct such brackets in such a way that the circuit wires may be easily passed through them and that they may be readily applied to a wall or an outlet box. A further object of the invention is to so construct a bracket of this class that it may be made at minimum cost, polished or finished without danger of breakage of any of the parts, and which when the parts are assembled and held in place will conceal the fastening devices and thus present an attractive appearance.

In carrying out my invention I employ a sheet metal casing, comprising a hollow canopy and a hollow arm which carries on its outer end a nipple and a support for the outer end of the rod which secures the bracket to the crowfoot or support attached to the wall of the outlet box therein. This rod firmly secures the bracket in place, and the circuit wires extend through the arm and through the nipple carried by the arm. In order to cover the outer end of the arm and to conceal the fastening devices I employ a cap having an opening which receives the outer end of the arm, and another opening through which the nipple extends. The edge of the cap around the opening fits snugly against a bead or shoulder formed on the outer end of the arm and the cap is held firmly in place by a nut which engages the nipple and presses the cap against the nipple-carrying extension of the arm.

In the accompanying drawings:—

Figure 1 is a perspective view of an electric light bracket embodying my improvements, certain interior parts being shown by dotted lines.

Figure 2 is a longitudinal central section thereof.

Figure 3 is a perspective view of the outer end of the bracket arm showing how the nipple is applied to its extension and how the fastening rod is connected. This figure also shows the cap detached and the cap-attaching nut.

The particular design of canopy and bracket arm shown is a preferred one, but my invention may be embodied in brackets of other artistic designs.

As illustrated, the bracket comprises a sheet metal canopy A and a hollow arm B. In the bracket shown, the arm B is made separate from the canopy and is connected therewith at b in a well known way. The outer end of the arm B is formed in a novel way. It has a bead or shoulder c which provides a seat for the cap D and it has a support e for the fastening rod E. Said bracket is also formed with an extension or lip f which carries a nipple F. The nipple is firmly attached to the extension f by the flanges shown and it is also preferably soldered for additional security.

The rod E is headed at its outer end g and its threaded inner end carries a nut G which engages the crowfoot, spider or support H which is attached to the side wall or to the outlet box therein. By means of this rod the bracket may be secured firmly to the support and it is surrounded by the canopy and its arm. In order to conceal the fastening device at the outer end of the bracket and produce an attractive appearance, I employ a cap D which fits over the end of the arm and over the nipple. This cap is formed with an opening d through which the outer end of the arm extends and with an opening d' through which the nipple projects. When the cap is applied to the bracket, it is first passed over the nipple and then turned to the position shown in Figure 2, when the edge of the opening d is firmly seated against the bead or shoulder c. Then the nut N is applied and screwed home in such manner as to firmly lock the cap in place.

The circuit wires may be applied in any preferred manner either in the shop or when the bracket is being installed. These circuit wires are passed through the bracket and through the nipple in well known ways.

A very important feature of the invention is that it enables me to polish or finish the exposed parts of the brackets without danger of breaking projecting parts. The extension f which carries the nipple F need not be polished as it is concealed by the cap when the parts are assembled. Heretofore in brackets of somewhat similar construction, when the outer end of the arm

was applied to the polishing wheels, and the arm was polished in the neighborhood of the nipple, the nipple was often broken off which has been a serious obstacle, but according to my invention the extension of the arm is not polished but left in a rough condition. It will be further observed that a smooth and even finish is given to the exterior of the bracket, the outer end of the fastening rod being surrounded by the cap while in many other constructions the head of the rod was exposed. The cap is separable from the bracket and may be polished separately and given a fine finish. It is important that this part of the bracket should be given the best finish possible.

It will also be observed that there are no loose or supplemental parts employed for connecting the cap with the bracket. The lug *e* is formed integrally with the bracket arm. The nipple is firmly secured to the bracket, and the nut is made strong and durable as is apparent from the drawings. As shown in Figure 2, the cap is so formed around the opening *d'* that when applied to the bracket and when the nut is screwed home, the cap will firmly engage the outside of the extension *f*. The nipple *F* may be used to connect the bracket with a lamp socket, or the nut may be used for that purpose. As shown, the nut carries a loop which forms no part of the subject matter herein claimed. By detaching the nut the cap may be easily removed, and the wires may be easily inspected or adjusted. Thereafter the parts may be quickly reassembled. If necessary, after the cap is removed, the fastening rod may be disconnected from its support and the bracket as a whole withdrawn.

I claim as my invention:

1. An electric light bracket comprising a hollow arm formed at its outer end with a bead, a nipple carrying extension and an inwardly extending lug engaging a fastening rod; and a cap seated against said bead and concealing said lug.
2. An electric light bracket comprising an arm formed at its outer end with a lug en-

gaging a supporting rod and a nipple carrying extension; a nipple in said extension, and a cap fitted on the outer end of the arm through which the nipple extends and which conceals the lug. 50

3. An electric light bracket comprising an arm formed at its outer end with a bead, a lug engaging a supporting rod, and a nipple carrying extension; a nipple in said extension, a cap resting against the bead and extension to conceal the extension and lug and through which the nipple extends, and a nut engaging the nipple to hold the cap in place. 55

4. An electric light bracket comprising an arm formed at its outer end with a bead, a lug engaging a supporting rod, and a nipple carrying extension, all of said parts being integral; a nipple in said extension, a cap resting against said bead and through which the nipple extends, and means engaging the nipple to hold the cap in place. 60

5. An electric light bracket comprising an arm, an integral projecting lip at the outer end of the arm, a nipple carried by said lip, and a cap fitting over the outer end of the arm to conceal said lip, said cap having an opening through which the nipple extends. 75

6. An electric light bracket comprising an arm, a projecting lip at the outer end of said arm, a nipple carried by said lip, a cap fitting over the outer end of the arm to conceal said lip and having an opening through which the nipple extends, and means on the nipple directly engaging the cap to hold the latter in place. 80

7. An electric light bracket comprising an arm, an integral projecting lip at the outer end of the arm, a nipple fastened in said lip, a cap fitting over the outer end of the arm and engaging said lip thereby concealing the same, and having an opening through which the nipple extends, and adjustable means on the nipple and directly engaging the cap to clamp the parts in assembled relation. 90

In testimony whereof, I have hereunto subscribed my name.

PAUL J. PFEIFER.
